UNITED STATES PATENT OFFICE.

WILLIAM F. LAUTENSCHLAGER, OF CINCINNATI, OHIO.

MOTOR-DRIVE.

No. 853,703.

Specification of Letters Patent.

Patented May 14, 1907.

Application filed March 2, 1907. Serial No. 360,224.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Motor-Drives, of which the following is a specification.

I have shown my invention applied to a sewing machine, as this application is very useful in illustrating the mode of operation and the utility and desirability of my invention, although it is obvious that the invention is also applicable to other machines of similar or different character. In the operation of a sewing machine, it is sometimes desirable that the sewing operation on the machine shall continue uninterruptedly and evenly, for instance in making a long seam. Again, it may be desired to intermittently start and stop the sewing machine at exceedingly short intervals, as in making short seams, or shifting the goods between seams, as in tacking, bordering or seaming gloves, shoe parts and the like. My improved device is very effective in accomplishing either purpose as the drive is such that the operative effect of the motor is communicated instantly and fully to the machine, and the machine may be instantly stopped, for instance at the end of a seam, by a brake operating on the motor and communicating its braking effect instantly to the machine, the continuity of operation of the machine being under instant control of the operator under all conditions.

It is the object of my invention to provide a motor drive in which the operating parts for effecting starting of the drive move transversely of the axis of the motor-shaft for relieving the latter of end strain, to provide a motor drive in which the said operating parts move about but independent of the motor-shaft, to provide means whereby the machine may be quickly started and stopped and, while operating, may be relieved of binding end stress upon the motor-shaft and to provide a motor drive in which the desired tight or loose connection between the motor-shaft and operating shaft of the machine may be instantly effected, and the invention will be readily understood from the following description and claims, and from the drawings, in which latter:

Figure 1 is a front elevation of my improved device applied to a sewing machine. Fig. 2 shows my improved device in similar

relation but in side elevation and with the sewing machine removed at the section-line $z-z$ of Fig. 1 for better illustration of parts. Fig. 3 is an enlarged side elevation of my improved device, partly broken away. Fig. 4 is an enlarged front elevation of the same, with the motor being broken away. Fig. 5 is a vertical section of my improved device on the line $y-y$ of Fig. 3, with the motor-casing partly in side elevation. Fig. 6 is a perspective view of the arm for the tightener pulley. Fig. 7 is a similar view of the operating arm. Fig. 8 is a section of the operating arm and its connections on the line $x-x$ of Fig. 3. Fig. 9 is a detail in section on the line $w-w$ of Fig. 3 showing the manner of braking the belt between the brake and motor-pulley. Fig. 10 is a detail in section on the line $v-v$ of Fig. 3 showing the manner of mounting the movable electric contact; and, Fig. 11 is a side elevation of the supporting-plate.

1 is a motor which may be of any style, size or capacity.

2 is a machine which it is desired to operate, shown as a sewing machine.

The motor 1 has a driving shaft 3 on which there is a driving pulley 4, and the machine has an operating shaft 5 on which there is a driven pulley 6. A belt 7 passes over the pulleys. The motor is shown as an electric motor, the drive-shaft 3 being shown as the armature-shaft of the motor. The shaft 3 is journaled in bearings 8 9. The bearing 8 is formed by an annular stud 10 in which there is a bushing 11, and over which there is an annular sleeve 12 which forms a journal-piece of a rocker-arm 13. The sleeve and bushing may be secured to the stud by a screw-plug 14. The rocker-arm 13 comprises an operating lever 15 having a bearing 16 journaled on the sleeve 12, this bearing forming an annular boss upon which a pulley-arm 18 is adjustably secured, as by means of having a split-bearing 19 on the pulley-arm about the boss of bearing 16, a clamping screw 20 securing the split-bearing to the boss in desirable positions so that the radial positions of the operating lever and pulley-arm may be relatively adjusted. Flange 21 on the operating lever positions the pulley-arm, and flange 22 on the sleeve positions the rocker-arm sidewardly. The pulley-arm has a pulley 23 thereon which forms a tightener-pulley for the belt 7. The tightener-pulley has a hub 24 and is jour-

naled on a stud 25 releasably secured to the pulley-arm in a bearing 26 on the latter, a suitable nut at the back of the stud screwing over a threaded rear end of the stud for securing the stud in place in the bearing.

31 is a brake having a braking face 32 adapted to engage preferably the outer face 33 of the belt 7, the braking force of the belt being communicated to the pulley 4 through the belt for forming a compressible braking substance between the braking face and the pulley for causing immediate stoppage of the motor-shaft. The belt 7 preferably extends upwardly, with its upper end of its loop received about the pulley 6 so that the weight of the belt is received by said pulley, thereby acting as a brake on the machine-shaft when the motor-shaft is thus stopped. The brake comprises a brake-arm 34 pivoted on a screw 35 screwing into a boss 36 on the operating lever and having a spring 37 between the swinging end of the brake, and the operating lever, between the rocking axis of the latter and the pivotal point of the brake therewith. This spring is secured preferably to a screw 38 in the brake and a screw 39 on the operating lever.

40 is a supporting-plate rigidly secured with relation to the motor casing and preferably forms the pulley-end for that casing. A pin 42 is secured in suitable position on the supporting plate, as in an aperture 43, the brake 31 engaging the pin for operating the brake. The brake has a recess 44 having a sloping wall 45, the normal position of the brake being such that the pin is in this recess, the recess permitting the brake to perform its braking function. When the rocker-arm is swung the sloping wall 45 is forced against the pin 42, thereby causing the braking face of the brake to recede from the pulley 4, the further swinging of the brake causing the engaging wall 46 on the brake-arm to travel along the pin 42. This wall preferably describes a circle having the rocking axis of the rocker-arm as its center when engaging the pin and thereby keep the braking face of the brake at uniform distance from the belt. The brake-arm is permitted to rock until the wall of a recess 47 engages the pin 42. The swinging of the rocker-arm will, under usual conditions, in the meantime have caused the tightener-pulley to engage and press upon the belt for tightening the same between the pulleys 4 and 6. The operation is such that the brake is first released, the tightening of the belt then taking place by the single movement of the rocker-arm. The return of the rocker-arm may be limited by a pin 48 secured to the supporting plate 40 in a recess 49, forming a stop for the rocker-arm.

51 is an electric contact for the electric motor and preferably comprises a carbon-contact 52 adjustably secured in a clamp 53,

the terminal being releasably secured in the supporting plate 40 in an aperture 54, the supporting plate being insulated therefrom by insulation 55, the terminal having a binding-post 56 at its inner end.

57 is a movable contact and is adapted to make and break contact with the contact 51. It is shown in the form of a bell-crank lever having a contact-arm 58 provided with a contact-point 59 mating the carbon-contact 52 and an operating-arm 60 adapted to be engaged by the rocker-arm. I have shown this engagement as accomplished through the means of an insulating roller 61 journaled on a pin 62 in the end of the operating lever 15. The movable contact 57 is pivoted on a pin 63 in an insulated bearing 64 in an aperture 65 in the supporting plate 40, a binding post 66 being on the pin. A spring 67 is secured to the movable terminal on a screw 68 and over insulation 69 on a pin 70 secured to the supporting plate in an aperture 71. This spring urges engagement of the electric contacts.

76 is a suitable treadle which, in the form 90 shown, is an imitation of an ordinary sewing machine treadle, which is pivoted at 77. A rod 78 connects the treadle and the rocker-arm for operating the rocker-arm from the treadle. Thus the treadle is provided with a 95 sideward extension 79 with which the rod 78 is articulated at 80, the upper end of the rod having a bearing 81 on the pin 62 with which it is releasably secured. In order to provide adjustment between the treadle and the 100 rocker-arm, I have shown the rod 78 comprising end sections adjustably secured together by means of a coupling 84, the rod-sections passing through apertures in said coupling, set-screws 85 securing said rod-sections therein in adjusted positions.

In operation, if it is desired to set the machine in motion, the treadle is swung on its pivot for depressing the operated swinging-end of the rocker-arm 13. This movement 110 first releases the brake by causing the sloping wall or contact-face 45 to move upon the pin or contact-part 42. The shape and relation of the sloping wall 45 to the pivot of the brake and the pin 42 are such that a resistance must be overcome in thus swinging the rocker-arm, which resistance is released as soon as the end of the sloping wall reaches the descending face of the periphery of the pin, which causes the further movement of 115 the treadle for swinging the rocker-arm to be accomplished with a jerk or accelerated movement which takes place just prior to the contact being made between the contact 57 and the contact 51, thereby causing this contact to be made with a snap movement for preventing arcing or sparking between the contacts, the motor being thereby instantly set in motion. The further movement of the 120 rocker-arm causes the tightener-pulley to 125 cause the belt to tighten. The further movement of the rocker-arm causes the tightener-pulley to 130

stretch the belt between the pulleys 4 and 6, thereby transferring the power of the motor-shaft to the machine-shaft and causing this transference of power to take place without lost motion in the drive. It will therefore be noted that the release of the brake, the driving of the motor, and the transference of the drive of the motor to the machine, take place in the sequence mentioned, the stoppage of power taking place in the reverse order. When it is desired to stop the machine and motor, the treadle is shifted so as to raise the swinging operated end of the operating lever, which first releases the tightener-pulley from its tightening action upon the belt, the insulated roller 61 then strikes the end of the operating arm 60 of the movable contact 57, thereby breaking contact between the electric contacts with a snap movement owing to the relation of said arm and the point of contact between the rocker-arm and the operating lever of the movable contact and owing further to the shape of the engaging wall 45 and its relation to the pin 42, which causes the breaking to take place with a snap movement for preventing arcing or sparking between the electric contacts, upon which the brake is instantly applied for stopping the motor and machine. I prefer to provide a cover 86 for the contacts, the cover being releasably secured to the supporting plate by screws 87 received by apertures 88 in the supporting plate, this cover being provided with a side aperture 89 for receiving the movable contact 57.

I prefer to make the parts of such form and to secure them in such relation that my improved drive may be used either for a right-hand drive or a left-hand drive, and for motors having operating-shafts rotating in respectively opposite directions while employing a straight belt, and in this connection it will be noted that the connecting-link 90 for connecting the ends of the belt extends sideways through the belt and also that the tightener pulley impinges the slack stretch 91 of the belt, the belt being operated in the direction of the arrow 92 in the present exemplification. In order to form proper grip between the belt and pulleys I prefer to provide the periphery of the pulley 4 with a comparatively deep groove 93, the pulley 6 having a similar groove. In order further that the drive may be used either for right hand or left hand drive, I place the contact 51 vertically above the rotary axis of the motor drive-shaft and provide the supporting plate 40 with an opening 65' for receiving the pin 63 of the movable contact 57 with its insulation 64. In similar manner I provide the supporting plate with an opening 71' similar to the opening 71 for the pin 70. I also provide the supporting plate with a threaded opening 49' similar to the opening 49 for receiving the pin 48, and with a threaded open-

ing 43' similar to the opening 43 for the pin 42. These respective openings are located equidistantly from the contact and the rotary axis of the motor-shaft at the respective sides of the supporting plate.

If it is desired to reverse the direction of drive the brake-arm is reversed upon the operating lever, that is, its outer face placed inwardly facing the operating lever, the operating lever being swung to the reverse side of the rotary axis of the motor-shaft under the opening 49' into which the pin 48 is placed, the pulley-arm 18 being similarly reversed upon the sleeve 12 so that the tightener pulley may impinge against the stretch 93 of the belt, which will then become the slack side of the belt. The cover 86 is also provided with an additional side-aperture 89' for receiving the contact-arm 58 when reversely placed.

The construction and arrangement of the parts permits instant stopping of the motor and of the machine upon the application of the brake, as the brake acts directly upon the power-transferring belt, forcing it against the motor-pulley for instantly stopping the same and also positively stopping the travel of the belt by its application to the belt. The machine-pulley is above the motor-pulley and the weight of the belt rests upon the machine-pulley, thereby acting as a brake upon the same for in turn promptly stopping the machine.

In my improved device the motor-shaft and the machine-shaft are relieved from undue strain, except the driving strain, in that the rocker-arm is supported on a rigid journal in such manner that its pivotal support or operation places no strain upon the motor-shaft, the moving parts moving in a direction at substantially right angles to the rotary axis of the motor-shaft, the construction permitting the motor-shaft to naturally follow its longitudinal vibrations induced by the electro-motive force between the fields 95 and the armature 96 on the motor-shaft, so that the armature may be free to follow the lines of electro-motive force and thus permit easy running of the motor, utilizing all the power in the motor to full efficiency. For aiding in this I prefer to make the groove 97 of the tightener pulley slightly wider or shallower than the groove in the driving and driven pulleys. For preventing overthrow of end movement in the armature-shaft I provide it with collars 98 adapted to be limited by the bearings of the armature-shaft.

In my improved motor drive the electric connections of the drive with the electric motor are preferably made in such manner as to be out of the way and preferably inside the supporting-plate, with the connection from an outside source of electricity for the motor and drive being made preferably by an ordinary electric plug connecting with the drive. Thus one of the motor-terminals 101 is elec-

trically connected with the binding-post 56 on the contact 51. The other of the motor-terminals 102 of the motor is electrically connected with the terminal 103 for the socket 104 shown in the supporting-plate and electrically connecting with the screw-ferrule 105 for the plug. An electric conductor 106 connects with the binding-post 66 on the pivot for the movable contact and with the terminal 107, being the other terminal for the plug. These terminals 103 107 are insulated respectively from the supporting-plate by insulations 108 and 109 and the ferrule 105 is insulated from the supporting-plate by insulation 110. The electric conductors 111 112 represent the conductors from a suitable source of electric energy and respectively connect with the outer electric conducting screw-ferrule 113 of the plug 114 at 115 and with the terminal 116, the latter adapted to engage the terminal 107, and thereby complete electric circuit in the motor when the contacts 51 and 57 are engaged in the operation of the motor-drive. The motor-terminals 101 and 102 may also connect respectively with the binding-post 66 and terminal 107, or may be arranged in reverse order at the respective binding-posts and terminals, the connection being such that power is transmitted to the motor when the energizing electric conductors are in place and the contacts 51 and 57 in contact.

Having thus fully described my invention what I claim as new and desire to secure by Letters Patent, is:

1. In a motor drive, the combination, with a motor-shaft, a bearing therefor, and a pulley for said shaft, of a brake and tightener-pulley oscillating about said bearing and movable in planes transverse to the longitudinal axis of said shaft.
2. In a motor drive, the combination with a drive-pulley, of an operating lever, a tightener-pulley therefor, a brake, a movable-contact arm, and means for moving said operating lever, tightener-pulley, brake and movable-contact arm in planes transverse to the rotary axis of said pulley.
3. In a motor drive, the combination, of a motor-shaft, a bearing therefor, an operating lever supported about said bearing, and a brake and a movable-contact lever moved by said operating lever in directions transverse to the longitudinal axis of said shaft.
4. In a motor drive, the combination, with a drive-pulley, of an operating lever, a brake operated thereby, said brake having a contact-face thereon, and a contact-part engaged by the latter for resisting the movement of said brake and causing its release with a snap movement.
5. In a motor drive, the combination, with a drive-pulley, of an operating lever, a brake operated thereby, said brake having a contact-face thereon, a contact-part engaged by

the latter, a movable electric-contact operated by said operating lever constructed and arranged for first resisting release of said brake, and then making electric contact for the motor with a snap movement.

6. In a motor drive, the combination, with a drive-pulley, of an operating lever and a tightener-pulley arm having adjustable connection therebetween; a tightener-pulley on said arm, and a brake on said lever, substantially as described.

7. In a motor drive, the combination, with a driving shaft and pulley therefor, a tightener-pulley, an operating lever for the same, a pivot for said operating lever independent of said shaft, an electric-contact arm, a brake pivoted to said operating lever, and means for moving said operating lever, brake and electric-contact arm in directions laterally of the vertical plane of the longitudinal axis of said shaft.

8. In a motor drive, the combination with a driving shaft and pulley therefor, of a tightener-pulley, an operating lever for the same, and electric-contact lever, a brake pivoted to said operating lever, a bearing for said shaft about which said operating lever is pivoted, and means for moving said operating lever, brake and electric-contact lever in directions laterally of the vertical plane of the longitudinal axis of said shaft, said brake having a contact-face thereon, and a contact-part for the latter arranged for resisting the disengagement of said brake and moving said electric-contact lever with a snap movement, substantially as described.

9. In a motor drive, the combination with a driving shaft and pulley therefor, of a tightener-pulley, an operating lever for the same, a spring-urged electric-contact lever, a spring-urged brake pivoted to said operating lever, a bearing for said shaft about which said operating lever is pivoted, and means for moving said spring-urged lever and spring-urged brake in directions laterally of the longitudinal axis of said shaft, substantially as described.

10. In a motor drive, the combination with a motor-pulley and a driven pulley, said pulleys arranged for having a belt travel thereabout, of a tightener-pulley, an operating arm and a brake having a contact-face, and a contact part for said contact-face, constructed and arranged for initially resisting release of said brake and then permitting movement of said arm with an accelerated movement.

11. In a motor drive, the combination with a motor-pulley and a driven pulley, said pulleys arranged for having a belt take thereabout, of a tightener pulley, an operating arm and a brake having a contact-face, a contact-part for said contact-face, and electric contacts, the said operating arm causing the making and breaking of contact of said elec-

- tric contacts, and constructed and arranged for first resisting release of said brake and then permitting relative movement between said electric contacts with a snap movement, said 5 tightener-pulley being operated by said arm.
12. In a motor drive, the combination, with a motor-pulley and a driven pulley, the pulley adapted for having a belt travel thereabout, of a tightener-pulley, an arm therefor, a 10 brake on said arm having a contact-face thereon, a contact part for said brake and an electric contact adapted to be moved by said tightener-pulley arm, the relation of said contact-face and contact-part being such as to 15 resist the release of said brake and permit the continuing movement of said arm with an accelerated motion for moving said electric contact with a snap movement, substantially as described.
13. In a motor drive, the combination, with a motor-shaft and pulley and a driven pulley adapted for having a belt travel thereabout, of a tightener-pulley, an arm therefor, a 15 brake on said arm having a contact-face thereon, a contact-part for said brake, an electric contact adapted to be moved by said tightener-pulley arm, the relation of said contact-face and contact-part being such as to 20 resist the release of said brake and permit the continuing movement of said arm with an accelerated motion for moving said electric contact with a snap movement, and a bearing for said shaft, said arm being pivoted about said bearing, substantially as de- 25 scribed.
14. In a motor drive, the combination with a motor-pulley and a driven pulley adapted for having a belt travel thereabout, of a tightener-pulley, an arm therefor, a 30 brake on said arm having a contact-face thereon, a contact-part for said brake, and an electric contact adapted to be engaged by said tightener-pulley arm, the relation of said contact-face and contact-part being such as 35 to resist the release of said brake and permit the continuing movement of said arm with an accelerated motion for moving said electric contact with a snap movement, said operating lever being articulated for adjusting 40 its operating end relatively to its pulley end, substantially as described.
15. In a motor drive, the combination, with a motor-pulley and a driven pulley, the 45 pulleys adapted to have a belt travel thereabout, of an operating arm, a tightener-pulley therefor, a brake, means for urging said 50 brake toward said first-named pulley for normally clamping said belt between said 55 brake and pulley, a contact-face on said 60 brake and a contact-part engaging therewith so arranged as to initially resist release of 65 said brake, the said operating lever and brake swinging at substantially right angles to the rotary axis of said first-named pulley, sub- 70 stantially as described.
16. In a motor drive, the combination, with a motor-pulley and a driven pulley, the 75 pulleys adapted to have a belt travel thereabout, of an operating arm, a tightener-pulley therefor, a brake, means for urging 80 said brake toward said first-named pulley for normally clamping said belt between said 85 brake and pulley, a contact-face on said 90 brake and a contact-part engaging therewith so arranged as to initially resist release of said 95 brake and then permit accelerated move- 100 ment of said operating arm, the said operating arm and brake swinging at substantially right angles to the rotary axis of said first-named pulley, and an electric-contact lever 105 adapted to be engaged by said operating arm and positioned for being relieved therefrom at the beginning of said accelerated move- 110 ment thereof, substantially as described.
17. In a motor drive, the combination, with a motor-pulley and a driven pulley, the 115 pulleys adapted to have a belt travel thereabout, of an operating arm, a tightener-pulley thereon, a brake, means for urging said 120 brake toward said first-named pulley for normally clamping said belt between said 125 brake and pulley, a contact-face on said 130 brake and a contact-part engaging therewith so arranged as to resist release of said brake and permit further movement of said arm with an accelerated movement, the said operating lever and brake swinging at substantially right angles to the rotary axis of said first-named pulley, an electric-contact lever adapted to be engaged by said operating arm and positioned for being relieved therefrom at the beginning of said accelerated movement thereof and arranged for braking electric contact with an accelerated movement at the end of the return movement of said operating lever, substantially as described.
18. In a motor drive, the combination of a rocker-arm, a tightener-pulley therefor, a 140 brake pivoted to said rocker-arm and having a contact-face, a contact-part for said contact-face, and an electric-contact lever, said 145 rocker-arm and lever having insulated moving agency therebetween, constructed and operating, substantially as described.
19. In a motor-drive, the combination of a 150 rocker-arm, a tightener-pulley therefor, a 155 brake pivoted to said rocker-arm and having a contact-face, a contact-part for said contact-face, an electric contact-lever, said 160 rocker-arm and lever having insulated moving agency therebetween, and a stop for said 165 rocker-arm, constructed and operating, substantially as described.
20. In a motor-drive, the combination of a 170 rocker-arm, a tightener-pulley therefor, a 175 brake pivoted to said rocker-arm and having a contact-face, a spring between said rocker-arm and brake, a contact-part for said contact-face, and an electric contact-lever, said 180 rocker-arm and lever having insulated mov- 185

ing agency therebetween, constructed and operating, substantially as described.

21. In a motor drive for an electric motor, the combination with a plate, of an operating lever, a brake operated by said lever, electric contacts, electric terminals and electric connections at the rear of said plate connecting one of said electric contacts and one of said terminals with the motor-terminals and connecting the other of said electric contacts and the other of said terminals with each other.

22. In a motor drive for an electric motor, the combination, with a plate, of an operating lever, a tightener-pulley therefor, electric contacts the making and breaking of the contact whereof being effected by said lever, terminals for a source of electric energy, and electric connections between said terminals and the motor-terminals and electric-contacts arranged in rear of said plate.

23. In a motor drive for an electric motor, the combination, of an operating lever, a tightener-pulley therefor, electric contacts the making and breaking of the contact whereof being effected by said lever, terminals for a source of electric energy terminating in a plug-socket and having electric connection with the motor-terminals and said electric contacts.

24. In a motor drive for an electric motor having a pulley-end comprising a supporting-plate and a plug-socket, of an operating lever, a tightener-pulley therefor, electric contacts the making and breaking of the contact whereof being effected by said lever, and terminals for a source of electric energy terminating in said socket and having electric connection with the motor-terminals and said electric contacts.

25. In a motor drive for an electric motor, the combination with a plate of an operating lever, a brake operated by said lever, a pair of electric contacts, a pair of electric terminals and electric connections at the rear of said plate connecting one of said contact-

parts and one of said terminals with the motor-terminals and connecting the other of said contact-parts and the other of said terminals with each other, said terminals being received in a plug-socket for electrically connecting the same with a source of electric energy by means of an electric plug received by said socket.

26. In a motor drive, the combination with a motor, and a pulley therefor, of an electric contact located above the rotary axis of said pulley, a movable-contact arm extending laterally from said first-named contact, an operating arm therefor, of a tightener-pulley for said operating arm, a supporting plate for said electric contacts, said supporting plate having securing means thereon for said movable-contact arm equidistant from said first-named contact and the rotary axis of said pulley at the respective sides of said first-named contact and said rotary axis.

27. In a motor drive, the combination with a motor and a pulley therefor, of an electric contact located above the rotary axis of said pulley, a pivoted contact arm extending laterally from said first-named contact, an operating arm therefor, a tightener-pulley for said arm, a supporting plate for said electric contact, a brake for said operating arm, a contact-part for the latter, a stop-pin for said operating arm, and positioning means on said supporting plate equidistant from said first-named contact and the rotary axis of said pulley for the pivot of said contact-arm, contact-part and stop-pin at the respective sides of said first-named contact and the rotary axis of said shaft, substantially as described.

In testimony whereof I have subscribed my name hereto in the presence of two subscribing witnesses.

WILLIAM F. LAUTENSCHLAGER.
